UNITED STATES PATENT OFFICE.

GEORGE L. JENKINS, OF PHILADELPHIA, PENNSYLVANIA, ASSIGNOR TO
THE AUSTIN, NICHOLS & COMPANY, OF NEW YORK, N. Y.

DESIGN FOR A BOTTLE.

SPECIFICATION forming part of Design No. 25,943, dated August 18, 1896.

Application filed June 19, 1896. Serial No. 596,219. Term of patent 14 years.

To all whom it may concern:

Be it known that I, GEORGE L. JENKINS, a citizen of the United States, residing at Philadelphia and State of Pennsylvania, have invented and produced a new and original Design for Bottles, of which the following is a specification.

In the accompanying drawings I have illustrated the design.

Figure 1 is a plan view showing the oval form of the complete bottle. Figs. 2 and 3 are sectional views a quarter-turn from each other; Fig. 4, a side view, and Fig. 5 a side view a quarter-turn from Fig. 3.

The leading feature of my design consists in a bottle having a flaring body and of greater width from side to side than from front to back, so as to give it a slightly-flattened appearance. The bottle is provided with a flar-

ing lip *a*, extending to the neck *b*, and from the neck the body of the bottle curves outwardly and then downwardly at an inward inclination to a foot *c*, where it curves outwardly again to form said foot, the bottom of the bottle being slightly concave. The lip and neck of the bottle are perfectly round, while the body and bottom of the bottle are elongated or flattened in the direction of the sides.

I claim—

The design for a bottle herein shown and described.

In testimony whereof I affix my signature in presence of two witnesses.

GEORGE L. JENKINS.

Witnesses:

GEO. H. BURGIN,
G. ERNEST PIXTON.
